UNITED STATES PATENT OFFICE.

FRANK KUHN AND FRANK E. SHAILOR, OF DETROIT, MICHIGAN; SAID SHAILOR
ASSIGNOR TO SAID KUHN.

ELECTRIC HEATER.

1,154,410.

Specification of Letters Patent. Patented Sept. 21, 1915.

Application filed January 31, 1914. Serial No. 815,748.

To all whom it may concern:

Be it known that we, FRANK KUHN and FRANK E. SHAILOR, citizens of the United States of America, residing at Detroit, in the county of Wayne and State of Michigan, have invented certain new and useful Improvements in Electric Heaters, of which the following is a specification, reference being had therein to the accompanying 10 drawings.

The invention relates to electric heaters of that type in which the heat developed in a naked resistor is distributed by radiation, the construction being more particularly 15 adapted for broilers and toasters.

In the drawings, Figure 1 is an end elevation partly in cross section of the heater; Fig. 2 is a longitudinal section; Fig. 3 is an enlarged cross section; and Fig. 4 is a 20 plan.

In the construction of toasters and broilers where the heated resistor is arranged in a horizontal plane, it is necessary to provide a supporting grid for the work. It is also 25 desirable to furnish intermediate support for the resistor to prevent the sagging of the same, and where a naked resistor is employed these supports must be insulated. With the present construction we have de- 30 vised a grid which, in addition to its function of supporting the bread or other article to be toasted or broiled, also forms a support for a naked resistor.

Still another feature of our improvement 35 is to arrange the resistor in such relation to the bars of the grid that the latter will not appreciably interfere with direct radiation.

In detail, A is a suitable outer frame, 40 which may be supported in any way, as by the legs B arranged at the corners thereof.

C is a grid frame composed of longitudinally extending bars D and cross bars E, the ends of which are supported in notches 45 in the outer frame A.

Each of the bars D is preferably formed from a folded strip of sheet metal having a crimp or bead F therein. Between the two plies of the strip is arranged the shank G 50 of a hanger G' for supporting the resistor,

and to prevent short circuiting a refractory insulating material H, such as mica, is arranged intermediate the shank and the plies of the strip. The hanger G' is preferably formed of a sheet metal stamping having an I'-portion twisted into a plane transverse to that of the shank portion and apertured for the passage of the resistor.

I is the resistor, preferably in the form of a helical coil of wire which is threaded 60 through the eyes G' and is therefore suspended by the same beneath and in the plane of the strips D of the grid. Where the length of the resistor is greater than the length of the strips D, it may be passed from 65 one strip to the other as indicated at I', Fig. 4.

The supporting frame or stand is preferably provided with a shelf J arranged beneath the resistor, which permits of utilizing 70 the downward radiation as well as the upward radiation from the resistor. By reason of the fact that the resistor helix is of greater diameter than the thickness of the strip D and is arranged in the plane of said 75 strip, the latter will not interfere greatly with the upward direct radiation, while the slight shielding produced by the strip will merely prevent overheating in the line which is nearest to the radiating surface. Thus 80 a very uniform heating effect is produced, with the advantage of the quick action due to the exposed or naked resistor.

What we claim as our invention is,—

1. In an electric heater, the combination 85 with a grid frame comprising a plurality of parallelly-arranged bars and connecting cross bars, of a resistor in the form of a helical coil extending parallel to the longitudinal bars beneath the same and in the 90 central plane thereof, the diameter of the coil being greater than the thickness of the bars, and insulated supports for said resistor from said bars.

2. In an electric heater, the combination 95 with a bar, of a resistor, and a hanger for supporting said resistor from said bar, said hanger having a portion apertured to receive said resistor and twisted into a plane transverse to the central plane of said bar. 100

3. In an electric heater, the combination with a grid frame comprising a plurality of parallelly - arranged bars and connecting cross bars, of a resistor in the form of a 5 helical coil of greater thickness than the bars, extending parallel to the longitudinal bars beneath the same and in the central plane thereof.

In testimony whereof we affix our signatures in presence of two witnesses.

FRANK KUHN.
FRANK E. SHAILOR.
